Attorney

UNITED STATES PATENT OFFICE

GEORGE D. BARNES, OF PENN YAN, NEW YORK

CIGARETTE EXTINGUISHER

Application filed March 31, 1930. Serial No. 440,442.

This invention appertains to tobacco users appliances and more particularly to a novel cigarette holder.

One of the primary objects of my invention is to provide a cigarette holder having means associated directly therewith for extinguishing a cigarette, said means including a sleeve slidably associated with the holder and movable over the free end of the holder into more or less intimate contact with the cigarette so as to snuff the burning end thereof.

I am aware of the fact that there has heretobefore been proposed or provided a sliding sleeve on a cigarette holder, but solely for the purpose of protecting the cigarette and preventing the flying of ashes and sparks incident to driving or the smoking of a cigarette on a windy day. These sleeves are all spaced from the cigarette and allow the circulation of air around the cigarette for supporting the burning of the cigarette in contra-distinction to my invention in which the sleeve is snugly carried by the body portion of the cigarette holder and is adapted to slide over the cigarette in close contact therewith for snuffing the burning end.

Another salient object of my invention is to provide a cigarette holder and snuffing sleeve which can be made of paper so as to materially reduce the cost thereof and to permit the giving of a holder with each package of cigarettes sold.

Another salient object of my invention is the provision of a cigarette holder embodying a cylindrical cigarette receiving portion having one end contracted to form a mouth piece and the opposite end flanged for facilitating the snuffing and the compression of the butt of the cigarette into the holder with a sliding snuffing sleeve mounted on the holder having a resilient flanged end for engaging the flanged end of the holder for limiting the outward sliding movement of the sleeve on the holder and for permitting the snug engagement of the sleeve with the cigarette.

A still further object of my invention is to provide a cigarette holder of the above character, which will be durable and efficient in use, one that will be simple and easy to manu-

facture, and one which can be placed upon the market at an extremely low cost.

With these and other objects in view, the invention consists in the novel construction, arrangement and formation of parts, as will be hereinafter more specifically described, claimed, and illustrated in the accompanying drawing, in which drawing:—

Figure 1 is a side elevation of my improved cigarette holder showing the same in use with the snuffing sleeve in retracted position.

Figure 2 is a longitudinal section through my improved cigarette holder showing the same in its extended operative snuffing position.

Figure 3 is a rear end elevation of the improved holder, and

Figure 4 is a transverse section through the same taken on the line 4—4 of Figure 1.

Referring to the drawing wherein similar reference characters designate corresponding parts throughout the several views, the letter A generally indicates my improved cigarette holder, which comprises an elongated cylindrical holder barrel portion 5 which is preferably made from paper either rolled or compressed into shape. This barrel 5 is of a uniform diameter throughout its length, but the rear end thereof is slightly compressed as at 6, while the forward end thereof is flanged or slightly flared outwardly as at 7. It is to be noted that while the rear end of the barrel 5 is compressed as at 6, the same is still left in its cylindrical form so that the same can be grasped by the lips of the user similar to the ordinary cigarette, the barrel being made of paper, is of extremely light weight.

Slidably mounted on the barrel 5 in snug engagement therewith is the snuffing sleeve 8. This snuffing sleeve is likewise made of paper and can either be rolled into the desired shape or compressed into shape. The rear end of the snuffing sleeve is flanged inwardly as at 9 and this flange is more or less of a resilient character due to the material from which the sleeve is made and is adapted to engage the flange 7 for limiting the outward sliding movement of the sleeve 8 on the

barrel 5, when the sleeve is moved to its extended position.

In use of my improved holder, the sleeve 8 is pulled rearward on the barrel 5 as shown 6 in Figure 1 after which the cigarette, indicated by the reference character C, is slightly compressed and forced into the forward end of the barrel. The cigarette C can now be smoked in the usual way and when it is de- 10 sired to extinguish the cigarette it is merely necessary to slide the snuffing sleeve 8 outward over the burning end of the cigarette which will immediately put the cigarette out.

In view of the fact that the complete holder 15 is made from paper the same can be supplied to the trade very cheaply and it is proposed to give a holder with each package of cigarettes and thus each holder will only be used say twenty times.

20 Changes in details may be made without departing from the spirit or the scope of the invention, but:-

What I claim as new is:

As a new article of manufacture, a cigarette 25 extinguisher and snuffer, comprising an elongated cigarette holding barrel having one end flanged for the reception of a cigarette and its opposite end contracted, an elongated tapered sleeve slidable on the barrel and hav- 30 ing its rear end flanged and adapted to contact with the flange on the cigarette holding barrel for limiting the outward movement of the sleeve with respect to the cigarette holding barrel, said sleeve having an inner 35 bore of the same size as a conventional cigarette, and adapted to slidably contact with the outer face of a cigarette for extinguishing the same as the sleeve is moved in contacting longitudinal movement over the outer 40 face of the cigarette carried by the cigarette holding barrel, the flanged end of the sleeve being of resilient character to permit the flexing thereof when the sleeve is slid on the barrel to permit complete contacting relation 45 between the cigarette carried by the cigarette holding barrel and the inner face of the bore of the sleeve.

In testimony whereof I affix my signature.
GEORGE D. BARNES.
